COLLAPSIBLE TAPERED CARTON

Thomas J. Bruehl, Menasha, Howard N. Hovland, Appleton, and George E. Verhage, Neenah, Wis., assignors to Marathon Corporation, Menasha, Wis., a corporation of Wisconsin

Application June 9, 1955, Serial No. 514,212

4 Claims. (Cl. 229—39)

This invention relates to a carton commonly known in the trade as a tapered carton with an automatic bottom, the carton in cross-section being rectangular and other than square. In this construction, the carton is so formed that when the side walls of the carton are erected to form a sleeve the bottom-forming members of the carton automatically move to close the bottom end of the carton. Cartons of this sort are widely used in the packaging of many commodities, and have achieved particular popularity in the packaging of ice cream. For such purpose, where the appearance of the packaging medium is of great consequence in determining acceptance and sale of the cartoned product, it is important that the package or carton incorporate all possible features to render it attractive.

It has thus far been found impractical to manufacture a tapered automatic bottom carton of rectangular cross-section in which the carton has a regular, uniform and substantially symmetrical appearance. That is, it has been impractical to manufacture such a carton wherein opposite side walls of the carton are identical to each other and are inclined at the same angle with respect to the bottom of the carton, and the side edges of opposite walls are all inclined at the same angle with respect to the bottom. The failure to have these characteristics obviously detracts from the appearance of the erected carton. This failure has been due principally to the impossibility heretofore of manufacturing such cartons of various dimensions in accordance with a regular or standard procedure.

Accordingly, it is the principal object of this invention to provide a rectangular cross-section, tapered, automatic-bottom carton having the desired appearance above set forth, and to provide a procedure whereby such cartons may be manufactured regardless of particular linear dimensions desired.

In describing our invention, reference will be had to the attached drawings, in which

Figure 1 is a plan view of a blank for a carton incorporating our invention.

Figure 2 is a plan view, partially cut away, similar to Figure 1, but with certain portions of the blank in folded condition and with adhesive applied thereto,

Figure 3 is a bottom elevation of our carton in glued and partially assembled condition,

Figure 4 is a bottom perspective view of our carton in erected condition,

Figure 5 is an elevation view of one side of our erected carton,

Figure 6 is an elevation view of an adjacent side of our erected carton,

Figure 7 is a plan view of a carton side wall layout involved in working out the procedure of our invention,

Figure 8 is a plan view similar to Figure 7, but with two of the side walls overlying the other two walls, and

Figure 9 is a plan view similar to Figure 8, but with corrective factors applied to produce carton side walls in accordance with our invention.

2

Referring first to Figure 1, the carton blank (ordinarily paperboard) includes side walls 1, 2, 3, and 4 hingedly connected along score lines 5, 6 and 7, and a glue flap 8 hinged to a side edge of wall 1 along score line 9. The free side edge of wall 4 is indicated by numeral 31. Top closure flaps 10, 11, 12 and 13 are hinged to the top edges of side walls along score lines 14, 15, 16 and 17. Along the remote edge of flap 10 a male locking member 18 is formed and a cooperating female locking slit 19 is formed in flap 12, in the conventional manner.

Bottom closure flaps 20, 21, 22 and 23 are hinged to the bottom edges of the side walls along score lines 24, 25, 26 and 27, flaps 21 and 23 being divided into two parts by diagonal score or perforation lines 28. The remote portions of flaps 21 and 23 have cut outs or notches 29 formed therein for a purpose to be described later in detail.

With additional reference to Figure 2, in the initial step of forming the carton from a blank, bottom flaps 20, 21, 22 and 23 are folded upwardly to overlie the walls to which they are hinged. The portions of flaps 21 and 23 outward of perforation lines 28 are then reversely folded and a suitable conventional adhesive applied to the exposed surface of those flap portions and also to the upper surface of glue flap 8, this adhesive being indicated by reference numeral 30. Wall 4, carrying with it flap 23, is then folded about score line 7 to overlie wall 3, thus bringing the adhesive-coated portion of flap 23 into adhering contact with flap 22. Wall 1, carrying with it flaps 8 and 20, is then folded to overlie wall 2, bringing flap 20 into adhering contact with the exposed adhesive-coated portion of flap 21 and the adhesive-coated surface of flap 8 into adhering contact with wall 4 adjacent the free edge thereof. The thus-formed collapsed carton is briefly restrained in this essentially folded condition until the adhesive 30 has had time to form a secure bond between the related elements.

The collapsed carton thus formed may be erected by pushing inwardly upon opposed corners of the carton, as represented by score line 5 and 7, with the result illustrated in an intermediate stage in Figure 3 and in the final stage in Figure 4. The bottom flaps are so proportioned and arranged that as the erecting process is carried out there results a positive and interlocking engagement of the notches 29 of flaps 21 and 23, to prevent collapse of the carton from the erected position shown in Figure 4; and flap 22, which is of size to substantially completely close the bottom of the carton, lies innermost of the bottom flaps, to provide a substantially leakproof construction.

Figure 5 shows what might be either carton side wall 1 or wall 3, since in our invention these two walls are identical. The top and bottom edges of side walls 1 and 3 are parallel and the side edges have the same angular relationship to the bottom edge. Figure 6 represents either side wall 2 or 4, since these two walls are identical; the top and bottom edges are parallel, and the side edges have the same angular relationship to the bottom edge. However, the angular relationship of the side edges of walls 1 and 3 to their bottom edge is different from the angular relationship of the side edges of walls 2 and 4 to the bottom of those walls, as will later be described in detail.

Figure 7 represents a blank layout of the walls only of a carton, in which the side edges 109, 105, 106, 107 and 131 of all of the four walls 101, 102, 103 and 104 lie at the same angle with respect to the respective bottom edges L₁, W₁, L₂ and W₂. These inclinations each equal an angle 90° plus an angular increment *a*, these angular increments in Figure 7, although equal, being noted as *a*₁, *a*₂, *a*₃, *a*₄, *a*₅, *a*₆, *a*₇, and *a*₈. The walls of this carton

blank are identified by the reference numerals 101, 102, 103 and 104 in Figure 7, and correspond respectively to walls 1, 2, 3 and 4 in Figure 1, and the other elements similarly correspond.

With additional reference to Figure 8, when walls 104 and 103 are folded about edge 106 to overlie walls 101 and 102, it will be observed that edges 109 and 131 fail to coincide, for geometrical reasons which brief consideration will make apparent. While the exact folding technique employed here is different from that described in connection with Figures 1 and 2, the result is obviously the same and this method more clearly illustrates the problem. With this failure of coincidence, it is obviously impossible to make a carton from the blank of Figure 7, and it will be clear that this impossibility cannot be removed by variation in the method of folding. The conclusion is necessarily reached that if there is to be a tapered carton which in cross-section is rectangular and other than square, it will be impossible to have the side walls bear equal angular relationship to the bottom of the carton. This invention presents a procedure for determining the angular relationship that must be utilized to bring into coincidence side edges 109 and 131 and thus presents a carton which can be manufactured for the intended purpose.

With further reference to Figures 7 and 8, the solution to this problem, which comprises the heart of the invention, is approached by ascertaining that the initial step in obtaining coincidence of side edges 109 and 131 involves moving each of points d (intersection of edges 109 and L_1) and e (intersection of edges 131 and L_1) half way toward each other, to meet at point f . In order to present an attractive and regularly shaped carton, it is necessarily kept in mind that opposed side walls must in final condition be identical to each other and with their side edges equally inclined to the bottom of the carton.

With point g (intersection of edges 106, W_1 and L_2) as a center, an arc is drawn connecting points d and e , with point f at its mid-point. The equal radius lines connecting center g with points d , f and e are denoted as N_1 , N_2 and N_3 .

The solution of the problem of the equal angular distances through which points d and e must be moved to coincide at f , which angles are identified as α_1 and α_2 , may take the following form:

L , W and angle α are known, assumed quantities, and

$$L_1 = L_2 = L \quad \alpha_1 = \alpha_2 = \alpha_3 = \alpha_4 = \alpha_5 = \alpha_6 = \alpha_7 = \alpha_8 = \alpha$$

$$W_1 = W_2 = W \quad \alpha_1 = \alpha_2 = \alpha \quad \text{angle } R_1 = 180^\circ - (\alpha_6 + \alpha_7) = 180^\circ - 2\alpha = R_2 = R \quad N_1 = N_2 = N_3 = N$$

Then,

$$N_1^2 = L_2^2 + W_2^2 - 2L_2 W_2 \cos R_1$$

$$\text{angle } l = \arccos \frac{W_1^2 + N_3^2 - L_1^2}{2W_1 N_3}$$

$$\text{angle } w = \arccos \frac{L_2^2 + N_1^2 - W_2^2}{2L_2 N_1}$$

$$\alpha_1 + \alpha_2 = l - w = 2\alpha$$

By substitution,

$$2\alpha = \arccos \frac{W^2 + N^2 - L^2}{2WN} - \arccos \frac{L^2 + N^2 - W^2}{2LN}$$

$$2\alpha = \arccos \frac{W^2 + L^2 + W^2 - 2LW \cos R - L^2}{2W\sqrt{L^2 + W^2 - 2LW \cos R}} - \arccos \frac{L^2 + L^2 + W^2 - 2LW \cos R - W^2}{2L\sqrt{L^2 + W^2 - 2LW \cos R}}$$

$$= \arccos \frac{2W^2 - 2LW \cos R}{2W\sqrt{L^2 + W^2 - 2LW \cos R}} - \arccos \frac{2L^2 - 2LW \cos R}{2L\sqrt{L^2 + W^2 - 2LW \cos R}}$$

$$= \arccos \frac{2W(W - L \cos R)}{2W\sqrt{L^2 + W^2 - 2LW \cos R}} - \arccos \frac{2L(L - W \cos R)}{2L\sqrt{L^2 + W^2 - 2LW \cos R}}$$

$$= \arccos \frac{W - L \cos(180^\circ - 2\alpha)}{\sqrt{L^2 + W^2 - 2LW \cos(180^\circ - 2\alpha)}} - \arccos \frac{L - W \cos(180^\circ - 2\alpha)}{\sqrt{L^2 + W^2 - 2LW \cos(180^\circ - 2\alpha)}}$$

$$\alpha = \frac{1}{2} \arccos \frac{W + L \cos 2\alpha}{\sqrt{L^2 + W^2 + 2LW \cos 2\alpha}} - \frac{1}{2} \arccos \frac{L + W \cos 2\alpha}{\sqrt{L^2 + W^2 + 2LW \cos 2\alpha}}$$

Referring to Figures 7, 8 and 9, the application of angle α to the assumed carton blank involves using edge or score line 106 as a fixed base line. If angle α is applied as a negative or subtractive increment to angle α_4 , it will be apparent that the blank at point e will be raised to position f . Conversely, if α is applied as a positive or additive increment to angle α_5 , point d will be lowered to position f . Negative application of α to angle α_5 will cancel positive application to α_2 , and similarly with respect to positive application to α_6 and negative to α_7 , insofar as movement of the wall bottom edges is concerned. It is also readily observed that negative application of α to α_8 coupled with positive application to α_1 , results solely in creating coincidence of edges 109 and 131. The resulting construction is as shown in Figure 9 in full lines, the phantom lines showing the initial construction of Figure 8.

In summary, the above application of angular increment α to the assumed angular disposition of the side wall side edges relative to the bottom edges results in increasing the angle as to the longer side walls (101 and 103) and by the same amount decreasing the angle as to the shorter side walls (102 and 104). Thus, the opposite side walls are identical to each other, each side edge of opposite side walls lies at the same angle relative to the bottom edge, and the erected carton will be of rectangular cross-section. An attractive and symmetrical elevational appearance of the carton necessarily follows.

It will now also be clear that our end product is a carton which can in fact be manufactured. Since edges 109 and 131 coincide, a glue tab or panel such as 8 (Figure 1) can be applied to either of walls 101 and 104 for adhesion to the other of those walls, and bottom and top flaps similarly provided.

To achieve the desired volume or capacity of the finished carton it is only necessary to determine by simple mathematical formulae the height of the carton necessary in relation to the now known cross-section.

Reflection now reveals that through the help of a simple mathematical formula we can provide an attractive carton as previously indicated, the only requirements being initial determination of base lengths of the side walls and assumption of the average of the angles at which we wish the side edges of the walls to be disposed relative to the base.

As an example of the use of our formula, we can assume that it is desired to manufacture a carton in which the base (L) of one pair of opposed side walls is to be three inches, the base (W) of the other pair of two inches, and the average assumed side edge angle 105° ($= 90^\circ + 150^\circ = 90^\circ + \alpha$).

$$L = 3 \quad W = 2 \quad \alpha = 15^\circ$$

$$\alpha = \frac{1}{2} \arccos \frac{W + L \cos 2\alpha}{\sqrt{L^2 + W^2 + 2LW \cos 2\alpha}} - \frac{\frac{1}{2} \arccos \frac{L + W \cos 2\alpha}{\sqrt{L^2 + W^2 + 2LW \cos 2\alpha}}}{\frac{1}{2} \arccos \frac{L + W \cos 2\alpha}{\sqrt{L^2 + W^2 + 2LW \cos 2\alpha}}}$$

Substituting known and assumed values,

$$\alpha = 3^\circ 04'$$

Applying these values to Figures 7 and 8, with the result

shown in Figure 9, edge-defining score lines 109, 105, 106, 107 and 131 lie at an angle $a+90^\circ+\alpha$ with respect to the side wall bottom edges, while these lines be at an angle $a+90^\circ-\alpha$ with respect to these edges.

It will become apparent that the solution of the principal problem might be approached in other ways, but ending with the same result, without departure from the basic elements of this invention. For example, with the same known, assumed quantities as used in the preceding solution,

$$N_1^2 = L_2^2 + W_2^2 - 2L_2W_2 \cos R$$

$$\frac{L_1}{\sin l} = \frac{N_3}{\sin R_2} \quad \frac{W_2}{\sin w} = \frac{N_1}{\sin R_1}$$

$$l = \arcsin \frac{L_1 \sin R_2}{N_3} \quad w = \arcsin \frac{W_2 \sin R_1}{N_1}$$

$$\alpha = \frac{l-w}{2}$$

By substitution,

$$\begin{aligned} \alpha &= \arcsin \sin \frac{1}{2} \left(\arcsin \frac{L \sin R}{N} - \arcsin \frac{W \sin R}{N} \right) \\ &= \frac{1}{2} \left(\arcsin \frac{L \sin 2a}{\sqrt{L^2 + W^2 + 2LW \cos 2a}} - \right. \\ &\quad \left. \arcsin \frac{W \sin 2a}{\sqrt{L^2 + W^2 + 2LW \cos 2a}} \right) \end{aligned}$$

Again, if we assess values $L=3$, $W=2$, $a=15^\circ$, this method results in the solution $\alpha=3^\circ 04'$, as before.

Thus our invention involves not only the use of a definite formula, but also separately the employment of a method whereby adjustments to unworkable assumed carton dimensions are made in a set pattern to provide a perfectly workable and attractive carton.

Brief reflection will make obvious the fact that the invention here involved is independent of the method of folding the carton blank, and is equally applicable to carton blanks folded as in Figure 1 and as in Figure 8.

Having now described and illustrated our invention, it must be understood that no limitations are to be applied except as set forth in the appended claims.

We claim:

1. A collapsible four walled carton having an automatic bottom, the top and bottom of the carton being co-parallel, the walls of the carton being inclined with respect to the bottom, opposed walls being identical and inclined at the same angle with respect to the bottom, adjacent walls being inclined at different angles with respect to the bottom, the carton in cross-section being rectangular

and other than square, the carton having given length and width dimensions of the bottom and an assumed height, the side edges of one opposed pair of walls being inclined with respect to the bottom at an angle $90^\circ+\alpha+\alpha$ and the side edges of the other pair of opposed walls being inclined with respect to the bottom by an angle $90^\circ+\alpha-\alpha$, in which α is an assumed angular increment by which said side edges are on the average desired to vary from perpendicular to the bottom and

$$10 \quad \alpha = \frac{1}{2} \arcsin \frac{W + L \cos 2a}{\sqrt{L^2 + W^2 + 2LW \cos 2a}}$$

$$15 \quad \frac{1}{2} \arcsin \frac{L + W \cos 2a}{\sqrt{L^2 + W^2 + 2LW \cos 2a}}$$

L and W being respectively the given length and width dimensions of the bottom.

2. A carton according to claim 1, further characterized by the fact that the side edges inclined at the angle $90^\circ+\alpha+\alpha$ are the side edges of the side walls having the greater bottom dimension.

3. A collapsible four-walled carton having an automatic bottom, the top and bottom of the carton being co-parallel, the walls of the carton being inclined with respect to the bottom, opposed walls being identical and inclined at the same angle with respect to the bottom, adjacent walls being inclined at different angles with respect to the bottom, the carton in cross-section being rectangular and other than square, the carton having given length and width dimensions of the bottom and an assumed height, the side edges of one opposed pair of walls being inclined with respect to the bottom at an angle $90^\circ+\alpha+\alpha$ and the side edges of the other pair of opposed walls being inclined with respect to the bottom by an angle $90^\circ+\alpha-\alpha$, in which α is an assumed angular increment by which said side edges are on the average desired to vary from perpendicular to the bottom and

$$40 \quad \alpha = \frac{1}{2} \left(\arcsin \frac{L \sin 2a}{\sqrt{L^2 + W^2 + 2LW \cos 2a}} - \right.$$

$$45 \quad \left. \arcsin \frac{W \sin 2a}{\sqrt{L^2 + W^2 + 2LW \cos 2a}} \right)$$

L and W being respectively the given length and width dimensions of the bottom.

4. A carton according to claim 3, further characterized by the fact that the side edges inclined at the angle $90^\circ+\alpha+\alpha$ are the side edges of the side walls having the greater bottom dimension.
